UNITED STATES PATENT OFFICE

125,918

DESIGN FOR A FLUORESCENT LIGHTING FIXTURE

Charles F. Johnston, Beaver, Pa., assignor to The
Phoenix Glass Company, Monaca, Pa., a corpo-
ration of West Virginia

Application October 4, 1940, Serial No. 95,638

Term of patent 14 years

To all whom it may concern:-

Be it known that I, Charles F. Johnston, a citizen of the United States and resident of Beaver County, in the State of Pennsylvania, have invented a new, original, and ornamental Design for a Fluorescent Lighting Fixture, of which the following is a specification, reference being had to the accompanying drawing, forming a part thereof.

In the drawing:

Figure 1 is a view in perspective of the fluorescent lighting fixture showing my new design.

Fig. 2 is an enlarged cross-sectional view taken on the line 2—2 of Fig. 1. The support in Fig. 2 is broken away for convenience of illustration.

The fixture end shown to the left is the same as the end shown to the right.

I claim:

The ornamental design for a fluorescent lighting fixture, substantially as shown and described.

CHAS. F. JOHNSTON.
